[57] CLAIM

The ornamental design for a trailer ball hitch cover kit, as shown and described.

DESCRIPTION

FIG. 1 is an environmental perspective view of a trailer ball hitch cover kit showing my new design;

FIG. 2 is a front elevational view of the hat element with the head element removed, the rear, the right side, and the left side being a mirror image thereof;

FIG. 3 is a top view thereof;

FIG. 4 is a bottom view thereof;

FIG. 5 is a front elevational view of the hat element;

FIG. 6 is a rear elevational view thereof;

FIG. 7 is a top view thereof;

FIG. 8 is a left side elevational view with the right side being a mirror image thereof; and,

FIG. 9 is a bottom view thereof.

The broken line showing of the vehicle bumper is for illustrative purposes only and forms no part of the claimed design.
